DUMP CAR DOOR CONTROL MEANS

Einar O. Lunde, Wyckoff, N. J., assignor to Magor Car Corporation, New York, N. Y., a corporation of Delaware

Application September 19, 1952, Serial No. 310,447

4 Claims. (Cl. 105—272)

This invention relates to dump car door control means. 15 The invention is more particularly concerned with a dump car wherein the body thereof is supported on an underframe for tilting movement toward one side or the other thereof, and wherein one or more doors are provided at each side of the body and pivotally connected thereto adjacent their lower ends, and a novel linkage disposed beneath the floor of the car body and operatively associated with the doors for permitting opening thereof upon tilting movement of the body.

It is a primary object of the invention to provide door control means in a dump car having a tiltable body wherein a door at each side of the body is normally retained in closed position, and wherein, upon tilting of the body toward one side or the other the corresponding door will be permitted to open under the action of gravity.

A further object of the invention is to provide control means for doors at the opposite sides of the tiltable body of a dump car which normally precludes opening of the doors, and which is operative upon tilting movement of the body to permit the door at the side of the body in the direction of tilting movement to open while maintaining the door at the opposite side in closed position.

Other objects and advantages of the invention will become apparent in the course of the following detailed description, taken in connection with the accompanying drawings, wherein:

Fig. 1 is a transverse section of the car body, with portions of the supporting wheels in dot-and-dash lines and showing the door control means in a normal position.

Fig. 2 is a transverse sectional view similar to Fig. 1 showing the car body partially dumped and the door at the dumping side being partially opened.

Fig. 3 is a fragmental transverse sectional view corresponding to Figures 1 and 2 and showing the car body fully dumped and the door at the dumping side fully opened.

Fig. 4 is a plan view showing the relative positions of the several components of the door control means at one end of the car.

Referring now in detail to the drawings, the body 10 includes a floor 11 and opposite side doors 12 and 12a.

Brackets 13 and 13a are rigid with the body framing and depend from the body floor 11. Fulcrum pins 14 and 14a are supported by the brackets 13 and 13a and normally rest in bearings 15 and 15a which are rigidly mounted on the body bolsters 16 and 16a.

The body is provided with opposite side skirts 17 and 17a which are slotted as indicated at 18 at the left of Fig. 1 for receiving the lower ends 19, 19a of door arms 20, 20a and said lower arm ends are pivotally connected to the body framing as at 21, 21a.

The arm ends 19, 19a are pivotally connected at 22, 22a to lengthwise adjustable link assemblies 23, 24 and 23a and 24a and the link assemblies are pivotally connected at their opposite ends as at 25, 25a to the adjacent ends of control arms 26, 26a which are pivotally mounted on pins 27, 27a, jointly with bell cranks 28, 28a and the

2

control arms and bell cranks are normally in contact as indicated at 29 in Fig. 1. The pins 27 and 27a are mounted on the brackets 13 and 13a.

The inner ends of bell cranks 28, 28a rotatably support rollers 30, 30a on pins 31, 31a and such rollers normally bear on the center sill 16b as indicated in Figures 1, 2 and 3.

Door control arm extensions 32, 32a have corresponding ends thereof loosely pivotally connected to the bell cranks 28, 28a, by the pins 31, 31a and the control arm extensions are pivotally connected intermediate their ends on pins 33, 33a which are respectively supported by the bearings 15a and 15 in co-axial relation to the fulcrum pins 14a and 14.

Control arm extension stops 34, 34a are supported in depending relation to the floor 11 and the doors and skirts are provided with cooperating stops 35, 36, 35a and 36a.

Since the construction and action of the described linkage is the same with each of the doors 12, 12a, the operation of the linkage will be described in connection with the door 12 which is shown in Figures 2 and 3 in the opening operation as is occasioned by tilting the body 10 to the left in a dumping operation.

Upon reference to Figure 1, it will be seen that in the normal position of the body, the door 12 is securely restrained against opening for the following reasons.

Any tendency of the door to open would cause counter-clockwise rotation of the arm end 19 about the pivot 21 and which through link assembly 23, 24 would tend to 30 rotate the control arm 26 and bell crank 28 clockwise about their common pivot 27. In the normal position, however, the bell crank 28 is restrained against clockwise rotation by the roller 30 which is in contact with the center sill 16b.

Upon reference now to Figure 2 wherein the body 10 has been partially dumped it will be observed that the body is being rotated in a counter-clockwise direction about the axis of the fulcrum pin 14.

The counter-clockwise rotation tendency of the arm end 19 will now be a fact since the elevation of pin 27 will permit the link assembly 23, 24 and the control arm 26 with the bell crank 28 to assume an angular position as shown.

At this point in the dumping operation, the roller 30 continues to contact the sill 16b and continues so until stop 35 engages stop 36.

Upon continued rotation of the body, as in Figure 3, the control arm 26 and bell crank 28 will separate, thereby providing for a full floating door.

Reverting to Figure 2, it will be observed that door 12a is maintained in closed position during the above described opening of the door 12 by the following means.

The door control arm extension 32a is pivotally mounted on pin 33a which is concentric to fulcrum pin 14 and the free end of the arm extension engages stop 34, and accordingly the extension is restrained against any rotation during the body tilting, and thus will hold the bell crank 28a, door control arm 26a, the link assembly 24a, 23a, and the door 12a in immovable position.

While I have disclosed the invention in accordance with a single specific structural embodiment thereof, such is to be considered as illustrative only, and not restrictive, the scope of the invention being defined in the subjoined claims.

65 What I claim and desire to secure by U. S. Letters Patent is:

1. In a dump car including a frame embodying a center sill, a body supported on the frame and having laterally opposed fulcrum pins normally engaged within open bearings on the frame for movement of either fulcrum pin upwardly from its bearing upon tilting of the body about

the other bearing, and a door at each side of the body and pivotally connected thereto at the lower edge of the door; the improvement comprising control means for each door, each of said control means comprising a control arm extension pivotally connected intermediate its ends to the opposed bearing in concentric relation thereto, a bell crank having a pin on one end thereof extending through a slot in one end of said extension, a roller rotatably supported on said pin and constantly bearing on said sill during body dumping about said other bearing, a control arm, the opposite end of said bell crank and the adjacent end of said control arm being pivotally connected to the body at a point intermediate the pin on said bell crank and the adjacent fulcrum pin, said bell crank and control arm having adjacent bearing faces above their pivotal connection normally in contact, and an adjustable link assembly pivotally connecting the opposite end of said control arm and said door below its pivotal connection with the body.

2. The structure according to claim 1, wherein said body is provided with a stop adjacent each side thereof, the other end of said extension adapted to engage one of said stops but being out of engagement therewith during said body dumping about said other bearing, the corre-

sponding end of the other extension being in engagement with the other of said stops during said body dumping about said other bearing.

3. The structure according to claim 1, wherein said link assembly comprises a tubular member pivotally connected to the control arm and a threaded rod member pivotally connected to the door and having adjustable threaded connection with the interior of the tubular member.

4. The structure according to claim 1, wherein said body is provided with a pair of laterally spaced depending brackets, to each of which is pivotally connected the cooperating bell crank and control arm associated with one door and which carries the fulcrum pin about which the body is tiltable upon door control actuation of the bell crank and control arm.
